(57) **CLAIM**

We claim the ornamental design for a stand for TV receiver, as shown and described.

DESCRIPTION

FIG. 1 is a front perspective view of a stand for TV receiver showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof; and,

FIG. 9 is another front perspective view, in which a TV receiver in broken lines is provided to illustrate an example environment.

The broken line showing of the TV receiver in FIG. 9 is for environmental purposes only and forms no part of the claimed design.
